UNITED STATES PATENT OFFICE.

PETER C. BRASHEAR, OF CASTLETON, NEW YORK, ASSIGNOR OF ONE-HALF TO
EMMONS BRYANT, OF CASTLETON, NEW YORK.

PAPER BOX.

1,075,812.

Specification of Letters Patent. Patented Oct. 14, 1913.

Application filed May 25, 1911. Serial No. 629,271.

To all whom it may concern:

Be it known that I, PETER C. BRASHEAR, a citizen of the United States, and a resident of Castleton, county of Rensselaer, and State of New York, have invented a new and Improved Paper Box, of which the following is a specification, reference being had to the accompanying drawings, in which—

Figure 1 is a plan of the cut blank from which the box is made; Fig. 2 is a perspective of the completed box; Fig. 3 is a partial section on lines III—III of Fig. 2 and Fig. 4 is a perspective showing the end flap in unlocked position.

15 The invention relates to that class of paper boxes which are made from one sheet or blank of paper, and which by folding of parts can be converted into a complete box without the use of fasteners other than the 20 folds of paper.

The novel features of my improved box are (1) the tabs at the upper corners of the box, which act as reinforcements, and prevent the box from tearing at such places; 25 (2) the configuration of the end flaps which cause their edges to abut against the upper inner surface of the side walls and lock the flaps and the box against horizontal movement, and (3) the end extensions of the end 30 flaps which lock the end flaps against vertical movement. These various novel features enable me to provide a box which is more durable than the paper boxes now in use, and at the same time provide positive 35 locking means which prevents the box from collapsing when in use.

Referring to the drawing, 2 is the bottom of the box having side walls 3 3', and side wall folds 4 4', which form the inner surface 40 of the side walls 3. The side wall folds 4 4' have tabs 5 5' projecting from their vertical edges adjacent to their tops, and the side walls 3 3' have extensions 6 6' extending from the ends of the side walls, and 45 having notched portions 7 7' which are adapted to interlock one with the other. The end walls 8 8' have flaps 9 9', and from the flaps 9 9' are extensions 10 10'. The tabs 5 5' are cut downward at a slight angle 50 from the top edge of the side walls 3 3' as are the side wall extensions 6 6' in order that in assembling the box, the flaps 9 9' of the end walls may be folded thereover. It will be seen that the flaps 9 9' near the point 55 of connection with the end walls 8 8' are

slightly cut or beveled inward in order to provide a clearance of the ends of the side walls 3 3'. Below the point or shoulder 11 the end folds are slightly broadened so that they may bear against the ends of the inner 60 side walls 4 4' and thus be locked against outward or horizontal movement. The extensions 10 10' are of the same width as the bottom of the box so that they abut against the ends of the inner side walls 4 4', and 65 hold the end walls against vertical movement.

The blank shown in Fig. 1 is folded into a box as follows: The side wall folds 4 4' are bent over on the lines a—a and are 70 preferably gummed to the inner surfaces of the side walls 3 3'. The side walls 3 3' fold on the line b—b and the side wall extensions 6 6' are then interlocked at the point 7 7'. This gives a general shape to the box. The 75 end walls 8 8' are folded on the lines c—c and the flaps 9 9' are then folded over the side wall extensions 6 6', and the reinforcing tabs 5 5' upon the line d—d so that the edges of the folds 8 below the point 11 11' will 80 snap in against the vertical edges of the inner side walls 4 4', and the end extension 10 will snap down under the lower edge of the inner side walls 4. It will thus be seen that from the points 11 11' to the points 85 12 12' the edges of the end folds will abut at the lower part of the vertical edges of the inner side walls 4 4', thus furnishing an extended locking surface against horizontal movement; and that the end extensions 10 90 10' will underlie and bear against the under surfaces of the edges of the inner side walls 4 4', thus giving a locking surface against vertical movement; and that this double lock 95 will be positive in effect. It will also be seen that the reinforcing tabs 5 5' not only reinforce and strengthen the corners of the box, but also provide against the end thrust, and serve to keep the end walls from bellying outward.

100 It is obvious that modifications may be made in my device without departing from my invention, since

What I claim is:

1. As a new article of manufacture, a 105 paper box formed from a single sheet or blank adapted to be folded to form, and comprising a rectangular bottom with side and end walls extending therefrom; each side wall comprising a side wall proper, a 110

lateral side wall extension, projecting therefrom at each end, said extensions being reversely notched to form an interlock when the parts are brought to position, a side wall 5 fold formed as an extension of the side wall proper, and a tab extending outwardly from each end of each side wall fold near the junction of said fold and the side wall; and each end wall comprising an end wall 10 proper, an end wall flap, and a flap extension, the side wall extensions, when the blank is folded to form, being embraced between the end walls and end wall flaps, and the tabs of the infolded side wall folds being 15 likewise embraced, while the end wall flap extensions bear upon the bottom and are interlocked between the bottom and the adjacent lower edges of the side wall folds.

2. As a new article of manufacture, a 20 paper box or tray formed from a single blank or sheet adapted to be folded to form and presenting, when so folded, outwardly-flaring sides and comprising a rectangular bottom with side and end walls extending 25 therefrom, each end comprising an end wall proper, an end wall flap, and a flap extension,

the ends or margins of the end walls diverging as they recede from the bottom, and the ends or margins of the flaps converging as they extend toward the flap extensions, each 30 of said margins being provided with a shoulder adjacent the line of fold between the end wall and end wall flap, and the flap extension being of a length substantially equal to the width of the bottom; and each 35 side wall comprising a side wall proper, with side wall extensions projecting laterally therefrom, and a side wall fold, the lines of bend or fold between said walls and their extensions diverging from the bottom 40 at an angle substantially equal to the divergence of the ends of the end walls aforesaid, and the ends of the side wall folds converging at a like angle toward the outer edge of the fold; and a tab extending outwardly 45 from each end of each side wall fold adjacent the line of fold between the side wall and the side wall fold.
